UNITED STATES PATENT OFFICE.

GEORGE J. MILLER, OF FREMONT, OHIO, ASSIGNOR TO THE MITCHELL REVERSIBLE WINDOW COMPANY, OF FREMONT, OHIO, A CORPORATION OF OHIO.

REVERSIBLE WINDOW.

No. 903,103.

Specification of Letters Patent.

Patented Nov. 3, 1908.

Application filed December 16, 1907. Serial No. 406,823.

To all whom it may concern:

Be it known that I, GEORGE J. MILLER, a citizen of the United States, and a resident of Fremont, in the county of Sandusky and State of Ohio, have invented certain new and useful Improvements in Reversible Windows; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to reversible windows of the horizontally pivoted type, and particularly to improvements in the sash-runners thereof; and it has for its object the provision of a runner of this class, which is materially lightened, simplified and improved in its construction over those heretofore employed for such purpose, whereby to increase its efficiency and enhance its practicability and commercial value.

25 The invention is fully described in the following specification and illustrated in the accompanying drawing, in which,—

Figure 1 is a partial perspective elevation of a window-casing and its windows, with the former partly in section. Figs. 2 and 3 are side perspective and end views, respectively, of a modified form of the runners, and Fig. 4 is a perspective view of a portion of one of the runners shown in Fig. 1.

35 Referring to the drawings, 1 designates the usual window-casing having the customary sash-grooves or runways 2 in its sides and 3 a sash mounted therein. The sash has a plate 4 secured to each side edge thereof by screws, or in any other suitable manner, and pivotally carried by the sash in abutment with the outer faces of these plates are the sash-runners 5, the construction of which forms the subject matter of this invention. The runners 5 are U-shaped in cross-section or in the form of channel-bars with the legs thereof extending outwardly from the sash and of suitable distance apart to operate freely within the grooves or runways 2 in the casing. One leg of each runner is transversely slit below the runner axis, as at 6, and the other leg is likewise slit above the runner axis, as at 7, to form lower and upper severed leg portions which are 55 turned outwardly and over the loop por-

tions of the runners in spaced parallelism therewith to form the diagonally disposed hooked flanges 8 and 9, respectively.

When the sash and runners stand in vertical parallel relation the hooked flanges 8 and 9 embrace the contiguous sides of the plates 4 near the upper and lower ends thereof, and their terminals project within recesses 10 formed in the edges of the sash at the inner sides of the plates 4 at such points, thus causing an interlocking of the plates 4 and runners 5 to prevent relative lateral movement thereof and to form a close joint between said parts to prevent the circulation of air therebetween. The void spaces in the legs of the runners caused by the turning up of the flanges 8 and 9 are filled by strips of metal 11, 11 which are suitably fashioned to form continuations of the legs. These strips are shown as being secured to the runners by having their inner ends shouldered around the contiguous ends of the runner legs and riveted or otherwise suitably secured thereto, and their inner longitudinal edges flanged and riveted to the loop portions of the runners. A U-shaped metal bracing-piece 12 is disposed within the channel of a runner at each end thereof and has its legs secured to the legs of the runner to laterally brace the same. The upper one of the pieces 12 is cut away to form an opening for the passage of the sash-cord 13 within the runner to attach to a hook 14 therein. If it is not desired to make the runners fire-proof, a block 15 of wood or other suitable material may be secured within the channels of the runners at the ends thereof and serve both to brace the legs and fill the spaces formed by the turning up of the flanges 8 and 9.

16 designates a spring pressed locking-bar, which is mounted in a suitable mortise in the sash side and operates through a longitudinal slot 17 in the associated sash-plate 4. This bar yieldingly coacts with the runner face to frictionally retain the sash in any desired position of adjustment relative to the runner, and when the sash is in its vertical or initial position the bar seats within a registering depression 18 formed in the runner face.

19 designates the bolts or trunnions which connect the runners and sash and form an axis on which they relatively swing.

It is apparent from the foregoing that I

have provided a sash-runner, which is simple, strong and durable and requires a minimum amount of material in its construction, thereby cheapening its cost of manufacture and enhancing its commercial value.

I wish it to be understood that I do not desire to be limited to the exact details of construction shown and described, as obvious modifications will occur to persons skilled in the art.

Having thus described my invention, what I claim as new and desire to secure by Letters Patent, is,—

1. The combination with a window-sash having diagonally disposed recesses in its side edges, of runners pivoted to the sash sides, said runners being U-shaped in cross-section and having diagonally-disposed portions of the legs thereof turned back upon the loop portions of the runners to form hooks which, when the sash and runners stand in parallelism, lock with the recesses in the sash to form a close joint between the parts and to limit their relative movements; and members secured to the runners to fill the vacancies in the legs occasioned by the turning up of said portions.

2. In combination, a window-sash having laterally facing recesses or grooves provided in the diagonally-disposed portions of its side edges, a runner pivoted to each side of the sash, said runner being U-shaped in cross-section and having integral diagonally-disposed hook-shaped flanges adapted to in-

terlock with the sash recesses or grooves to limit the relative movement of the parts, the flanges being formed by the turning up of portions of the runner legs, members secured to the runners to fill the leg vacancies made by the turning up of said portions, and bracing-pieces interposed between and secured to the runner legs at their ends.

3. In combination, a window-sash, plates secured to the sides thereof, a runner pivoted to each side of the sash in abutment with the plates, means coöperating with the sash and runners to frictionally retain them in relative adjustment, said runners comprising channel-bars having their legs slit at predetermined points therein and diagonally-disposed portions of the legs of a runner turned back upon the loop portion thereof to form hooks adapted to interlock with registering edges of the associated sash plate, a metal piece secured to each leg to form a continuation thereof whereby to fill the leg space made vacant by the turning back of said portions, and metal bracing-pieces secured between the ends of the associated legs, substantially as described.

In testimony whereof I have hereunto signed my name to this specification in the presence of two subscribing witnesses.

GEORGE J. MILLER.
